DES. 2063

as to

American Lead Pencil Company, of Hudson City, N.Y.

Letters Patent No 3063-Dated May 9, 1865.

Design for a Trade Mark to be used on Lead Pencils.

The schedule referred to in these Letters Patent and making part of the same.

To all whom it may concern:

Bent know that I, Joseph Scheeler, of the City, County and State of New York have invented a new Design for a Trade Mark, to be used on Lead Pencils and on Packages or Wrappers for containing the same, and I hereby declare that the following is a full clear and exact description of the same, reference being had to the accompanying drawing forming part of this specification, said drawing representing the design on an enlarged scale.

This design which may be printed directly upon the pencils, or upon the packages or wrappers containing them, or upon labels attached thereto, represents the figure of "America," standing upon the apex of a small dome or cupola upon which is a circular panel on which are the initial letters of United States in Roman capitals, the "U" being partly between the upper portions of the limbs of the "A."

The figure draped to the feet in female costume of the character of the period of ancient Greece, holds in one hand a sword, the point of which rests upon the dome, and holds a wreath in the other hand, which rests upon a shield supported upon the dome.

Upon the shield is represented the National emblem, the Stars and Stripes.

Upon the head of the figure is a helmet unadorned with a surrounding circle of stars, and an eagle for the crest.

What I claim as my design and desire to secure by Letters Patent is

The design and configuration of the trade mark
herein described and represented in the accompanying drawing.
